UNITED STATES PATENT OFFICE

120,886

DESIGN FOR A MEDAL

Theodore C. Glaser, Newark, N. J.

Application April 16, 1940, Serial No. 91,705

Term of patent 14 years

To all whom it may concern:

Be it known that I, Theodore C. Glaser, a citizen of the United States, residing in Newark, in the county of Essex and State of New Jersey, have invented a new, original, and ornamental Design for a Medal, of which the following is a specification, reference being had to the accompanying drawing forming part thereof.

In the drawing, Figure 1 is a front view of the medal. Figure 2 is a section on line 2—2 in Figure 1 and Figure 3 is a front view, the same as Figure 1, with the front panel in raised position, showing my new design.

I claim:

The ornamental design for a medal, as shown.
THEODORE C. GLASER.
